CONDENSER DEAERATOR

George A. Worn, Greenwich, Conn., and George W. Evans, Jr., Teaneck, N.J., assignors to The Lummus Company, New York, N.Y., a corporation of Delaware

Filed Dec. 14, 1955, Ser. No. 553,006

3 Claims. (Cl. 257—43)

This invention relates to improvements in steam power plant equipment and more particularly to improved condensing and deaerating apparatus for such a plant and this application is a continuation-in-part of our copending application, Serial Number 532,176, filed September 2, 1955, and entitled, "Condenser," now Patent No. 2,848,197.

A steam power plant employing a turbine normally includes, in addition to a boiler or steam generator, a series of feed water heaters and a surface condenser for the exhaust steam from the turbine. Steam is condensed in the condenser and the condensate is conducted from the hot well of the condenser through the feed water heaters in series and returns to the boiler. Within the heaters, the condensate is heated by steam which may be bled from one or more stages of the turbine. Such steam is condensed in its passage through the heaters and the condensate is also returned to the boiler. This condensate, together with make-up water, as required for the boiler, should be deaerated before introduction to the boiler and it is customary to provide a separate deaerator unit for that purpose. The deaerated water is then pumped from such unit through one or more heaters to the boiler.

An object of our invention is to provide a combined steam condensing and deaerating apparatus devised to obtain advantageous cooperation of condenser features with deaerating means.

A further object of our invention is to provide a construction of high vacuum, surface condenser adapted especially for large sizes in which each condenser tube contributes the maximum area possible to active condensation of steam.

A still further object of our invention is to provide an improved condensing unit wherein exhaust steam from a side exhaust or end exhaust turbine may be conveniently introduced through a side inlet in the unit with a resultant substantial saving in supporting structure and head room and wherein the inlet area of the nest of condensing tubes is at a maximum so that the velocity of the steam entering the nest of tubes is materially reduced and the paths of steam flow converge toward points of complete condensation.

Further objects and advantages of our invention will appear from the following description taken in connection with the accompanying drawings.

In the drawings:

Figure 1 is a vertical sectional view of a condenser unit embodying the invention, the section being on the line 1—1 of Figure 2;

Figure 2 is a vertical section on line 2—2 of Figure 1, partly broken away;

Figure 3 is a fragmentary enlarged sectional view showing in detail the deaerating means located in the steam inlet portion of the condenser of Figure 1;

Figure 4 is a modified form of Figure 3; and

Figure 5 is a diagrammatic top view of a portion of a steam power system embodying a side exhaust turbine and our invention.

2

The structure of the condensing unit shown in Fig. 1 includes a shell 10 horizontally disposed and formed at one side with a portion 11, which provides an inlet passage for exhaust steam from the turbine. The steam inlet 12 in portion 11 may be rectangular in vertical section having opposite walls 13, which converge outwardly from the shell to the steam inlet and terminate in horizontal portions 13a. Opposite walls 14 may converge outwardly from the shell to the steam inlet and terminate in vertical portions 14a, similar to portions 13a of the walls 13, and form therewith a frame for connection with the exhaust opening of the turbine.

The opposite ends of the shell are provided with flanges and have secured thereto respectively tube sheets 15 and 16 and water boxes 17 and 18. Tubes 19 connect to the tube sheets and are arranged in a nest comprising two or more equal banks 20 and 21 formed one above the other and spaced to define therebetween a horizontal central lane or lanes 23. Water box 18 has a horizontally, diametrically disposed pass partition 24 and two nozzles 25 and 26. Referring to Fig. 1, the nozzle 25 admits cooling water to the compartment below the pass partition for flow through the tubes of the lower tube bank 20 to the water box 17 and thence in reverse direction through the tubes of the upper bank 21 to the water box compartment above the partition and out through the nozzle 26. Thus, the condenser as illustrated is a two-pass unit but the number of passes may be varied by appropriate arrangements of pass partitions and nozzles.

Each tube bank has an air offtake baffle structure which includes wall 27, 28 and 29 and 30, 31 and 32, respectively; the ends of each baffle structure being open so that non-condensable gases may be withdrawn from both banks through nozzles 33 and 34. With each baffle structure is a portion of the tubes of the respective bank which act as an air cooler section. Also within each baffle structure are transversely disposed interleaving baffle plates 35 and 36, which are spaced to provide a tortuous path of flow for the non-condensable gases. A steam jet ejector, not shown, may be connected to nozzles 33 and 34 to maintain a desired vacuum. Such an ejector may deliver to the usual inter and after condenser combination, not shown.

Beneath the shell 10 there is a hot well 37, which extends along the major portion of the shell length and is of quite substantial depth and width to give it relatively large storage capacity. Within the upper portion of the hot well, there are deaerating means for the condensate drained from the tube banks. Such means includes perforated shower trays 38 and 39 with upturned outer edges. These trays extend horizontally the full length of the hot well but do not individually span the full width of the hot well. All of the shower trays are welded or otherwise suitably secured to the adjacent walls of the hot well. Air offtake pipes, not shown, may lead from opposite sides of the hot well, at points between trays 38 and 39, to the air offtake baffle structures. The hot well has a condensate discharge nozzle 40 leading from its lower portion.

Incorporated and coacting with the condenser tube banks 20 and 21 are condensate shower trays 41 and 42 for deaerating condensate from the respective tube banks. Tray 42, which is positioned within the horizontal central lane 23, receives most of the condensate from the tube bank 21 and showers such condensate to an underlying imperforate plate 43, which is shaped to direct the condensate to the rear side of the condenser shell where it falls to a point below the lower tube bank and is thereafter directed to the hot well. In showering from tray 42 to plate 43, the condensate from the upper tube bank is substantially reheated and deaerated. A weir 44 at the top of the hot well 37 and within shell 10 is provided

with notched portions 45 whereby condensate from plate 43 is collected in the troughs formed between the weir and shell and discharges in divided streams to tray 38. Final deaeration of the upper tube bank condensate occurs as it showers from trays 38 and 39 to the hot well with condensate from the lower tube bank. Tray 41, which underlies tube bank 20, receives most of the condensate from such lower tube bank and showers such condensate to the trays 38 and 39 in the hot well. In showering from the tray 41 to trays 38 and 39, the condensate from the lower tube bank is substantially reheated and deaerated. Final deaeration of the lower bank condensate occurs as it showers from trays 38 and 39 to the hot well with condensate from the upper tube bank.

All of the shower trays have their free edges turned up so that the condensate will collect sufficiently on the trays for passage through the perforations rather than spill ineffectually from one edge. The upper edge of the upturned tray portion is notched so that in the event of tray flooding, condensate pouring over a tray edge will fall in a plurality of streams.

Incorporated and coacting with the condensing apparatus there is apparatus for deaerating a charge of condensate returns from the feed water heaters and/or boiler make-up water. This deaerating apparatus includes a deaerating device A mounted within the steam inlet portion along the side wall 13. This device includes a plate 46 disposed parallel to the wall 13 and spaced therefrom. A plate 47 is located parallel to, and between plate 46 and wall 13. At an intermediate level in the height of plate 46, there is a perforated shower tray or deck 48 which extends from such plate to the upper edge of plate 47, terminating in an upturned edge 49. Along the lower edge, plate 47 has an inwardly extending perforated shower tray 50 terminating short of plate 46 and having an upturned inner edge. At a level between the deck 48 and tray 50 there is a perforated shower tray 51. This tray extends outwardly from plate 46, terminating short of plate 47 and has an upturned outer edge. The plates 46 and 47 and all of said trays extend the full distance between the steam inlet walls 14 and are welded or otherwise suitably secured to walls 14 and plates 46 and 47.

At the outer side of one of the walls 14 there is a pipe 52 to deliver the charge to the deaerator device. This pipe has a branch 53 which extends throughout most of the length of the deaerator and is spaced above deck 48 and has a row of spray nozzles 54 directed toward said deck. A collecting trough for the deaerated liquid is formed by the weir 44, shell 10 and wall 13 and underlies the deaerator device. The tray 50 of the deaerator device is spaced upwardly from said trough while the lower end of plate 46 extends partially within said trough.

As steam enters the condenser inlet 12 a portion of it enters the deaerator A by passage through the spaces between plate 47 and wall 13 and between trays 50, 51 and 48 thereby reheating condensate spraying from nozzles 54 as such condensate is deaerated by showering from tray to tray. Also, by admitting steam to the deaerator A the pressure on the liquid collected in the trough below such deaerator is equalized on each side of plate 46 whereby liquid collecting between plate 46 and wall 13 is permitted to flow to the inner side of plate 46 and thence to discharge over weir 44 to the hotwell 37.

In Figure 4 we have illustrated a modified form B of the deaerator to be located in the condenser steam inlet. This form of deaerator includes plate 46a disposed parallel to the wall 13 and spaced therefrom. At an intermediate level in the height of plate 46a, there is a perforated shower tray or deck 48a, which extends from such plate to wall 13 and is provided with overflow downpipes 55 open at both ends but sealed at the lower end in the condensate on deck 51a. At a level below deck 48a and pipes 55 is a perforated shower tray 51a. This tray extends outwardly from plate 46a, terminating short of the wall 13 and has an upturned outer edge. Below tray 51a

is tray 50a which extends inwardly from wall 13, terminating short of plate 46a. This tray likewise has an upturned free edge. Below tray 50a is a perforated tray 56 disposed in a manner similar to tray 51a. The plate 46a and all of said trays extend the full distance between the inlet walls 14 and are welded or otherwise suitably secured to walls 13 and 14 and plate 46a. Pipe 53a extends throughout most of the length of the deaerator and is spaced above deck 48a and has a row of spray nozzles 54a which direct condensate charge to said deck. The deaerator device B is spaced upwardly from the trough formed between wall 13 and weir 44 with the lower end of plate 46a extending partially within said trough.

As steam enters the condenser inlet 12 a portion of it enters the deaerator B by passage through openings 57 and thence between trays 56, 50a, 51a and 48a thereby reheating and deaerating condensate as it showers downwardly from tray to tray. As previously described the admission of steam to the deaerator equalizes the pressure on the liquid on either side of plate 46a.

Air offtake pipes 58 and 58a lead from the space between the trays 48 and 51 and 48a and 51a, respectively, of the deaerator devices A or B within the steam inlet. These pipes remove non-condensable vapors and extend across the condenser and then upwardly within the shell and open into one of the air offtake baffle structures at points adjacent the air-cooling tubes contained therein, keeping the air out of contact with the condensate from tube banks 20 and 21 so it will not be reabsorbed.

In the operation of the apparatus, exhaust steam passes from the turbine T (Fig. 5) into the condenser, and condensate is withdrawn from the hot well 37 through a pipe 59 and passed in succession through the tube side of a drain cooler C and a plurality of feed water heaters H, en route to the boiler, not shown. Steam is bled from one or more stages of the turbine through pipes P and P₁ and passed to the shell side of heaters H respectively, to heat the water flowing through the tube side of the heaters by indirect heat exchange. Condensate of the steam within the heaters may be passed through pipe 60 from one heater to another, and through a pipe 61 to the drain cooler C and thence through deaerating means located in the condenser inlet before joining the condenser condensate in the hot well 37. Make-up water may be supplied, as needed, to the system at any suitable point.

Usually a vacuum ranging from 26 to 29 inches will be maintained within the condenser and this vacuum will exist within each deaerator.

It is known that in order to obtain the necessary condensing surface without unduly increasing the size of the condenser, the tube spacing adjacent the steam inlet perimeter of the nest of tubes must of necessity be such as to occasion no objectionable loss in vacuum between the point or points of complete condensation within the tube nest and the steam inlet to the condenser. To overcome objectionable losses of vacuum, the cooling tubes 19 are distributed so as to increase the inlet area of the nest of tubes so that the velocity of steam flow entering the nest of tubes is materially reduced below that employed in ordinary condensers. Likewise the condensing surface is so distributed that the paths of steam flow converge toward the air offtake baffle structures.

To accomplish the above and primarily to eliminate the massive structure generally required to support the turbine above the condensing unit, the present invention utilizes a side inlet to the condenser with the tubes divided into separate independent groups having separate primary condensate deaerating means and separate air offtake structures. With such an arrangement the condenser may be positioned adjacent to the turbine affording better maintenance opportunity and substantially less supporting structure. The tubes are arranged for maximum inlet area for the steam with the condenser steam inlet facing directly into the turbine exhaust. The tubes of each group are distributed to obtain the advantage

gained by having the condensing surface so distributed that the areas of steam flow diminish from the steam space toward the air offtakes in substantially direct proportion to the decrease in condensation taking place along the paths of steam flow, or in direct proportion to the decrease in volume of uncondensed vapor along the path of flow.

While the invention is disclosed as employed in power plant service, it may be employed advantageously in other services requiring surface condenser equipment where it is particularly desirable to support the prime mover on the same level with such condenser. It is, of course, to be understood that the present disclosure of the invention is merely illustrative and in nowise limiting and that the invention comprehends such modifications as will fall within the scope of the following claims.

In the claims, the word "steam," except where identified with a steam power system, is intended to comprehend other vapors also, and the word "air," wherever it occurs, is intended to comprehend also other non-condensable gaseous media.

We claim:

1. In a surface condenser unit including a shell having a side steam inlet passage, a nest of substantially horizontal condensing tubes located within said shell and divided into at least two superposed groups of tubes, each group having substantially converging paths of steam flow, means for circulating cooling water through said tubes, said side steam inlet passage being defined by a top wall, side walls and an inwardly declining bottom wall, deaeration apparatus integrated with said condenser unit and located within said steam inlet passage for heating and partially deaerating water from an outside source, a hot well disposed below said tube nest to receive condensate from said nest and disposed to receive partially deaerated water from said deaeration apparatus, a deaerating device within said hot well for deaeration of said condensate and for final deaeration of the water received from said deaeration apparatus, and an air offtake means leading from a relatively cool portion of each group of tubes, the improved deaeration apparatus within said steam inlet passage comprising: a plate disposed substantially parallel to and spaced from the declining bottom wall thereby defining with said bottom wall a deaeration chamber within said steam inlet passage; a water delivery conduit leading from outside of the condenser unit, said conduit being in water delivery communication with said chamber and free from condensate receiving communication with the condenser unit to deliver to said chamber the water to be heated and partially deaerated; superposed trough-like shower trays located within said chamber below said delivery conduit and disposed so as to cause the water received from said delivery conduit to discharge downwardly and successively through said superposed trays as a plurality of fine

10
15

streams, said chamber having a steam inlet below said trays for admitting steam from said side steam inlet passage, said trays being arranged to cause serpentine flow of steam from said steam inlet between said trays across said streams; an air off-take conduit leading from said chamber at a level between the uppermost one of said trays and the next lower tray, said air off-take conduit leading to the relatively cool portion of one of said groups of tubes for passage of the air to the air off-take means associated therewith; and a trough disposed beneath said trays and extending between the terminal portion of said declining bottom wall and the hot well for collecting water discharged from said trays, the lower portion of said chamber defining plate extending into said trough to a point just short of the bottom thereof whereby water discharged from said trays collects within said chamber in one portion of said trough and after flowing under the lower edge of said plate discharges into the hot well from a second portion of said trough disposed outside of said chamber.

2. A surface condenser as claimed in claim 1 wherein the plate which is disposed within the side steam inlet passage so as to define, with the bottom wall of said inlet passage, a deaeration chamber and which extends into the trough disposed beneath the trays located within said chamber, contains the steam inlet for admitting steam from said steam inlet passage to said chamber for serpentine flow to the air offtake conduit leading from said chamber.

3. A surface condenser as claimed in claim 1 wherein the deaeration chamber, defined by the inclined bottom wall of the side steam inlet passage and a plate disposed substantially parallel to and spaced from said bottom wall, is provided with a baffle plate, disposed between said inclined bottom wall and said spaced plate, which terminates and supports at its upper edge the uppermost shower tray and which extends to and supports at its lower edge the lowest shower tray, said baffle plate defining with said bottom wall the steam inlet for admitting steam from said steam inlet passage to said chamber below said lowest tray for serpentine flow to the air offtake conduit leading from said chamber.
